UNITED STATES PATENT OFFICE.

LEON J. BARRETT, OF WORCESTER, MASSACHUSETTS.

PRUNING SHEARS.

Application filed September 11, 1922. Serial No. 587,514.

To all whom it may concern:

Be it known that I, LEON J. BARRETT, a citizen of the United States, residing at Worcester, in the county of Worcester and State of Massachusetts, have invented a new and useful Pruning Shears, of which the following is a specification.

The principal object of this invention is to provide a pruning shear capable of operation with sufficient multiplication of power to permit of cutting through a relatively large limb by hand.

The principal feature of the invention consists in an improved ratchet device and its connections for permitting of the use of the device for the purpose specified, employing a leverage of relatively large ratio.

The invention also involves improvements in the means for automatically throwing in 20 and disconnecting the ratchet and the relative arrangements of the parts for producing an effective device for this purpose with the great leverage ratio.

Reference is to be had to the accompanying drawings, in which

Fig. 1 is a side elevation of a pair of pruning shears constructed in accordance with this invention and shown in open position ready to start the cut;

Fig. 2 is an edge view of the same; and

Fig. 3 is a side view showing the device applied to a pole and operated by a flexible connection, and illustrating it in its cutting position with the knife almost through the cut.

Referring first to Figs. 1 and 2, I have shown the main member 10 consisting of a malleable iron casting preferably provided with a handle 11. On this casting is fixed by bolts 12 or the like a blade 13 of tool steel and shown as having a bevel cutting edge of arcuate form. Pivoted on a bolt 14 on this malleable iron casting is a ratchet segment 15. I have indicated in dotted lines an adjusting device for adjusting this ratchet member to take up wear. This is shown in the form of a nut 16 having teeth in which an adjusting pawl 17 is adapted to engage, but this is not shown in detail as it does not constitute a feature of this invention.

On this ratchet member are a series of ratchet teeth arranged concentric with respect to the bolt 14 and it is provided with two stops 18 and 19 at opposite ends for en-

gaging the handle 20 of a pawl 21 which is 55 adapted to engage the ratchet teeth. As the ratchet segment moves to either extremity, one of the stops engages the handle 20 and throws the pawl 21 in or out as the case may be. The pawl is held in either position by 60 a pin 22 on it engaging the rounded end 23 of a spring 24 mounted on the malleable iron plate 10. This spring is located in a recess 25 in this malleable iron plate, the wall of which has a projection 26 for engaging the 65 shank of the spring and forcing its end 23 always into contact with the pin 22.

Mounted on the ratchet plate 15, which is preferably of malleable cast iron, by means of bolts 27 is a cutting blade of tool steel 28, 70 but co-operating with the blade 13. This swings with the ratchet segment 15 about the pivot 14.

Pivotedly mounted on a bolt or stud 30 on the plate 10 is a handle 31 on which is 75 pivotally mounted on stud or bolt 32 a ratchet pawl 33. This handle 31 co-operates with the handle 11 and the pawl 33 engages the ratchet for operating the device. This ratchet pawl 33 has a spring 34 for normally 80 forcing it into contact with the teeth of the ratchet and it also has a recess with a projection 35 at its end for engaging a projection 29 on the pawl 21 and holding it out of engagement with the teeth at a certain time, as 85 will appear.

The operation of the device is as follows: With the parts in the position shown in Fig. 1, the handle 31 is drawn back. The spring 34 holds the pawl 33 in contact with the teeth 90 of the ratchet 15 and the spring 24 acts on the pin 22 to hold the pawl 21 also yieldingly in contact with the same teeth. As the handle 31 is drawn back away from the handle 11, the pawl 33 ratchets over the teeth 95 and then when the handles are forced together, the blade 28 is forced toward the other blade and into the wood if it is in contact with it. The number of teeth which will be passed over by each motion will depend 100 largely upon the resistance which the wood being cut offers. The operator can take a long or a short cut at each operation, as may be more convenient. During the operation, when the projection 35 on the pawl 33 comes 105 forward far enough, it will engage the projection 29 on the pawl 21 and force that pawl 33 out of engagement with the teeth,

moving the pin 22 over the elbow 23 at the same time.

Obviously, the hook blade 13 being hooked over the limb, the limb is not fully cut off until 5 the blade 28 moves far enough to contact with the highest point of the curve of the hook blade. It will be understood that the cutting ordinarily commences when the blade 28 first crosses the end of the hook blade if the device 10 is used on a limb of the maximum size. If used on a limb of smaller size, it will cut in after that point is reached. This prevents the blades crossing each other after the cut is commenced. The operator continues the 15 vibration of the handles until the limb is entirely cut off.

At this point, stop 18 engages handle 20 forcing pawl 21 out of contact with the teeth. The pin 22 slips over the elbow 23 of spring 20 24 and the pawl 21 is thus yieldingly held out of position. This is the position shown in Fig. 3, which will be presently described. Now, the shears can be opened to the position shown in Fig. 1.

25 Further continued motion of arm 31 and hence stop 18 forces projection 29 into engagement with projection 35 and pushes pawl 33 out of engagement with the ratchet teeth. This allows the ratchet 15, through the 30 action of the spring 36, to be returned to its original position, causing stop 19 to engage handle 20 and forcing pawl 21 back to its normal position in engagement with ratchet 15. The operation can then start over again.

35 It will be observed that a spring 36 normally pulls the ratchet plate 15 into a position to open the shears and constantly acts against the ratchet pawl 33.

In the form shown in Fig. 3, instead of 40 having two handles, I have shown the malleable casting 10 as mounted on a pole 40 and in place of the handle 11 I have shown a lever 41 operating in the same way, except that it is manipulated by a flexible connection 42 extending downwardly and alternately pulled and released to perform the cutting action in the same way as that described above. It is pulled up by a spring 43.

Although I have illustrated and described 50 only two forms of the invention, I am aware of the fact that further modifications can be made therein by any person skilled in the art without departing from the scope of the invention as expressed in the claims. 55 Therefore, I do not wish to be limited to all the details of construction herein shown and described, but what I do claim is:—

1. In a pruning shear, the combination of 60 a hook blade with a ratchet segment pivotally connected therewith, yielding means for moving said segment in one direction, a lever pivotally mounted with respect to said blade and having a pawl thereon for operating the ratchet against the action of said 65 spring, a second pawl pivotally mounted

with respect to said blade engaging said ratchet, and means for automatically moving the second pawl into or out of engagement with the ratchet at each end of the stroke of the ratchet segment. 70

2. In a pruning shear, the combination of a main blade, a supporting handle connected therewith, a hook-shaped blade mounted thereon, a ratchet segment pivotally mounted on said blade, a lever pivotally mounted 75 on the blade at a distance from the point where the segment is mounted on it and beyond the segment teeth, a pawl pivoted on said lever for engaging and operating the ratchet as the lever swings on its pivot, a second pawl mounted on the first named blade and having an arm projecting inwardly over the surface of said segment, said segment having fixed stops near its opposite ends for engaging said second pawl and swinging it back and forth into and out of engagement with the teeth of the ratchet. 80

3. In a pruning shear, the combination 85 of a main blade, a supporting handle connected therewith, a hook-shaped blade mounted thereon, a ratchet segment pivotally mounted on said blade, a lever pivotally mounted on the blade at a distance from the point where the segment is mounted on it and beyond the segment teeth, a pawl pivoted on said lever for engaging and operating the ratchet as the lever swings on its pivot, a second pawl mounted on the first named blade and having an arm projecting inwardly over the surface of said segment, said segment having fixed stops near its opposite ends for engaging said pawl and swinging it back and forth into and out of engagement with the teeth of the ratchet, the last named pawl having a 95 pin projecting therefrom, and a spring mounted on said blade having an elbow for engaging either side of said pin to hold the pawl either in or out of active position. 100

4. In a pruning shear, the combination 105 of a main blade, a handle connected therewith, a blade mounted thereon, a ratchet segment pivotally mounted on said blade, a lever pivotally mounted on the blade at a distance from the point where the segment is mounted on it and beyond the segment teeth, a pawl pivoted on said lever for engaging and operating the ratchet as the lever swings on its pivot, a second pawl mounted on the first named blade and having an arm projecting inwardly over the surface of said segment, said segment having fixed stops near its opposite ends for engaging said pawl and swinging it back and forth into and out of engagement with the teeth of the ratchet, the last named pawl having means for holding it yieldingly in or out of active position. 115

5. In a pruning shear, the combination 120

of a fixed blade, a supporting handle connected therewith, a second blade mounted thereon, a ratchet segment, a lever at a distance from the point where the segment is mounted, a pawl pivoted on said lever for engaging and operating the ratchet as the lever swings on its pivot, a second pawl having an arm, said segment having stops near its opposite ends for engaging said second pawl and swinging it back and forth into and out of engagement with the teeth of the ratchet.

6. In a pruning shear, the combination of a fixed blade, a supporting handle connected therewith, a second blade mounted thereon, a ratchet segment, a lever at a distance from the point where the segment is mounted, a pawl pivoted on said lever for engaging and operating the ratchet as the lever swings on its pivot, a second pawl having an arm, said segment having stops near its opposite ends for engaging said second pawl and swinging it back and forth into and out of engagement with the teeth of the ratchet, said pawls having interengaging means for forcing the first pawl out

of engagement with the ratchet teeth when the blades come to closed position.

7. In a pruning shear, the combination of a fixed blade, a supporting handle connected therewith, a second blade mounted thereon, a ratchet segment, a lever at a distance from the point where the segment is mounted, a pawl pivoted on said lever for engaging and operating the ratchet as the lever swings on its pivot, a second pawl having an arm, said segment having stops near its opposite ends for engaging said second pawl and swinging it back and forth into and out of engagement with the teeth of the ratchet, the second pawl having means adapted to engage the first pawl, when the second pawl is forced against one of said stops and forcing the first pawl out of engagement with the ratchet teeth, and a spring constantly acting on the ratchet to open the blades and bring the other stop into contact with said arm to release the first pawl.

In testimony whereof I have hereunto affixed my signature.

LEON J. BARRETT.
